(57) **CLAIM**

The ornamental design for a transportation communication device, as shown and described.

DESCRIPTION

FIG. 1 is an isometric front view of a transportation communication device showing our new design.

FIG. 2 is a side view of a transportation communication device showing our new design.

FIG. 3 is a top view of a transportation communication device showing our new design.

FIG. 4 is a front view of a transportation communication device showing our new design; and,

FIG. 5 is a bottom view of a transportation communication device showing our new design.

The broken lines depict portions of the transportation communication device that form no part of the claimed design. Moreover, the broken vertical lines illustrated in the Figures reflect ornamental features that form no part of the claimed design (the vertical lines do not define boundaries of claimed areas of the design).
